Specification of Letters Patent.

Patented Apr. 16, 1912.

Application filed January 11, 1910. Serial No. 537,466.

To all whom it may concern:

Be it known that I, WALTER J. MUNCASTER, a citizen of the United States, residing at Cumberland, in the county of Allegany and State of Maryland, have invented certain new and useful Improvements in Cranes, of which the following is a specification.

My invention relates to cranes, and particularly to a special form of pillar crane, peculiarly designed for the loading of box cars.

Heretofore, although there has been a great need and demand for a device for conveniently loading box cars, the problem has never been successfully solved, and it has been customary to load such cars by hand, or by means of trucks entering the car from an elevated platform. This latter method, while reasonably satisfactory, does not give means for depositing the articles in their final positions, and cannot be used with success in the case of very heavy or bulky objects. It has been particularly difficult to load pieces of any considerable length, as shafting or the like, into such cars, but by my invention even this is readily accomplished.

The principal feature of my invention is the use of a crane arm articulated at several appropriate points in its length, the various joints being so arranged, and the intervals between the joints being so proportioned, as to adapt the crane to the special service indicated.

I am aware that heretofore cranes having articulated arms have been used, but in such cranes it has been customary to provide but a single joint, which precludes the attainment of the advantages incident to my invention, as will become apparent.

In addition to the provision of a plurality of joints in the arm, my invention further contemplates the use of certain proportions contributory to more successful operation, and various other improvements in form and construction, which will be explained in connection with the preferred embodiment of the invention illustrated in the drawings, wherein:

Figure 1 is an elevation of a crane, showing the parts as they would appear assembled; Fig. 2 illustrates a modified form of pillar; Fig. 3 is an elevation, partly in section, of a portion of the structure illustrated in Fig. 1; and Fig. 4 is a diagram-

matic plan view, designed to show the method of loading a box car by the use of the crane illustrated in Fig. 1.

Referring to Figs. 1 and 3, 1 represents the post or pillar of the crane. This is set upright in a foundation constructed of concrete and steel, and consisting of a central pier 2 of concrete, through which pass in various directions steel beams 3, whose ends rest on the smaller concrete or stone piers 4. Thus the central pier need only be heavy enough to carry the vertical load, while the beams provide the necessary lateral stability. To secure a tight fit of the pillar in the pier 2, and to facilitate removal thereof at any time, iron collars 5 and 6 are set into the concrete to receive the lower end of the pillar. By this arrangement it is possible to construct the foundation prior to the setting up of the pillar, and as a convenient means of forming the socket, and of retaining the collars in position during the setting of the concrete, I use a tubular shell 7 which connects the two collars as shown. By this use of separate collars and a connecting tube, the castings are lighter and simpler than would be the case were the collars connected by a shell cast integral therewith, and the tubular shell may be made of light sheet metal. The crane arm is swiveled on the post 1 at 8 and 9, and consists of three sections 10, 11 and 12, successively hinged together at 13 and 14, and 15 and 16, as shown. Suspended from the extremity of the outer section is a hoist 17, of any well known type, and of a capacity suited to the crane. The hinges between the various sections of the arm and the swivel joint with the pillar 1 all include roller bearings to take the lateral stress, and ball bearings to take the vertical thrust. In the case of the swivels 8 and 9, the rollers 18 run on cylindrical portions 19 and 20 of the pillar 1, and are encircled by the bearings 21 and 22 formed in the section 10 of the crane arm. The bearing 21, which in this case is the upper one, has a race 23 formed on its lower face, and balls 24 are inserted between this race and the corresponding race 25, formed in a collar 26 removably attached to the pillar. The collar 26 is made removable to permit the withdrawal of bearing 22 over the end of the pillar. A flange 27, similar to collar 26, is formed on the pillar beneath bearing 22, to retain the rollers and exclude dust,

etc. In addition dust caps 28 are provided over both bearings. The hinges between sections are essentially identical with the above, and similar parts are numbered alike 5 in the drawings. Minor differences are the use of heavy rods or bolts 29, passing through bosses 30 of their respective arm sections 10 and 11, as the bearings for the rollers 18; the placing of the ball thrust 10 bearing beneath the lower bearings (as at 14 and 16); and the use of flanged collars 31 pinned to the rods 29 to serve a purpose similar to that of the flange 27. Obviously the location of the ball thrust bearing is a 15 matter of design, as is the number of such bearings used, but a single thrust bearing, located as shown, is usually sufficient.

The arm sections may be fabricated of structural shapes, as in the case of section 20 12, or may be cast of steel or iron, as in the case of sections 10 and 11. The particular form is not vital, but the construction indicated is believed to be desirable as contributing to rigidity. Any tendency of the 25 arm sections to sag so as to bring the various hinges out of a vertical direction would cause difficulty in handling of the crane, due to a tendency to swing to a particular position. When the sections are fabricated 30 from structural shapes, castings 32 and 33 are riveted thereto to form the hinge bearings.

In constructing a crane of this type, it is well to make the sections 10 and 11 of about 35 equal radial length, and the section 12 of about the combined length of 10 and 11; though I give these dimensions as suggestive, and do not absolutely limit myself thereto. The advantage of such proportions may be seen 40 from an inspection of Fig. 4 which is a diagram of a track T and a car C having a doorway D, and shows the method of inserting a long object O by means of my crane. The sections of the crane arm are 45 indicated by the numerals 10, 11 and 12, which correspond with the numerals already applied to these parts, the subscripts *a*, *b*, *c* and *d* indicating successive positions of the crane. It will be noted that the pillar 1 is 50 so set that the first arm section 10 swings entirely clear, and the section 11 may reach into the car. Then, by folding 11 upon 10, sufficient clearance may be had to allow section 12 to be swung toward either end of the 55 car, or be entirely withdrawn. Even though section 12 be longer than either of the others (and it might even be more than twice as long), and though section 12 be longer than the inside width of the car, it 60 is possible to swing the end of arm 12 to almost any point in the car. Usually, of course, it is desirable to make it as long as convenient handling permits.

My invention broadly contemplates the 65 use of three or more sections, with any suit-

able proportion of sections, and I do not limit myself to the proportions and construction set forth above except as specifically stated in the claims.

In cases where it is not necessary that the 70 crane arm shall swing entirely around the post, and in cases where the crane is to be attached to a wall or the like, the alternative construction illustrated in Fig. 2 may be used. The modification consists in the 75 forming of arm section 10 with a post 34, which turns in cast brackets 35 and 36 attached to the post or wall 37. Rollers 18 and balls 24 are used in these joints, the construction being closely similar to that already 80 set forth.

The particular form of foundation described is shown primarily to illustrate a satisfactory means of supporting such a crane, and not as being the only one suitable 85 to such service. It is believed, however, that because of the great lateral stability of such construction, and the economy in the use of material, it will be found particularly desirable for a crane of this type. 90

It is obvious that cranes of this type are adapted for loading any vehicle, whether constructed to move upon rails, as in the case of railway cars, or not. For instance, it might successfully be used to load canal 95 boats, or other boats, the principle of operation being the same as that described in connection with cars. In the claims, therefore, the terms "vehicle" and "runway for a vehicle" will be used in their broad sense. 100

Having thus described my invention, what I claim is:—

1. In a crane, the combination of a support; an arm section pivoted on said support; a second arm section pivoted to the 105 first arm section and approximately equal in length therewith; a third arm section pivoted to the second arm section and approximately equal in length to the first and second sections combined; and hoisting mechanism carried by the third section; the axes of all of the above named pivots being vertical. 110

2. In a crane, the combination of a support; an arm section pivoted on said support; a second arm section pivoted to the first arm section and approximately equal in length therewith; a third arm section pivoted to the second arm section and greater in length than either of the others; 115 and hoisting mechanism carried by the third section; the axes of all of the above named pivots being vertical. 120

3. In a crane, the combination of a support; an arm section pivoted on said support; a second arm section pivoted to the first arm section; a third arm section pivoted to the second arm section and greater in length than the second section; and hoisting mechanism carried by the third section; the 125 130

axes of all of the above named pivots being vertical.

4. In a crane, the combination of a support; an arm section pivoted on said support; a second arm section pivoted to the first arm section; a third arm section pivoted to the second arm section and greater in length than the first section; and hoisting mechanism carried by the third section; the axes of all of the above named pivots being vertical.

5. In a crane, the combination of a support; an arm section pivoted on said support; a second arm section pivoted to the first arm section; a third arm section pivoted to the second arm section and approximately equal in length to the first and second sections combined; and hoisting mechanism carried by the third section; the axes of all of the above named pivots being vertical.

6. In a crane, the combination of a support; a plurality of arm sections approximately equal in length and successively pivoted to the support and to each other; a terminal section pivoted thereto approximately equal to the aggregate length of the other sections; and hoisting mechanism carried by the terminal section.

30 7. In a crane, the combination of a sup-

port; a plurality of arm sections successively pivoted to the support and to each other; a terminal section pivoted thereto greater in length than any of the other sections; and hoisting mechanism carried by the terminal 35 section.

8. In combination with a runway for a vehicle, a support adjacent said runway; an arm section hinged on the support to turn clear of a vehicle on the runway; a plurality 40 of arm sections successively pivoted to the first arm section and to each other; and hoisting mechanism carried by the outermost section.

9. In combination with a runway for a 45 vehicle, a support adjacent said runway; an arm section hinged on the support to turn clear of a vehicle on the runway; a plurality of arm sections successively pivoted to the first arm section and to each other, the outermost section being the longest; and hoisting mechanism carried by the outermost section.

In testimony whereof I have signed my name to this specification in the presence of two subscribing witnesses.

WALTER J. MUNCASTER.
